UNITED STATES PATENT OFFICE

BENJAMIN S. NASH, OF SHORT HILLS, NEW JERSEY, ASSIGNOR TO THE STEARNS & FOSTER COMPANY, OF LOCKLAND, OHIO, A CORPORATION OF OHIO

DESIGN FOR TICKING

Application filed July 24, 1929. Serial No. 32,176. Term of patent 7 years.

To all whom it may concern:

Be it known that I, BENJAMIN S. NASH, a citizen of the United States, residing at Short Hills, in the county of Essex and State of New Jersey, have invented a new, original, and ornamental Design for Ticking, of which the following is a specification, reference being had to the accompanying drawing, forming part thereof.

In the drawing:—

The figure is a plan view of a piece of ticking, showing my new design.

I claim:

The ornamental design for ticking substantially as shown.

BENJAMIN S. NASH.
